CAN CLOSING MACHINE

Nelson Troyer and Paul E. Pearson, Seattle,
Wash., assignors to Continental Can Company,
Inc., a corporation of New York

Application March 26, 1930. Serial No. 439,137

36 Claims. (Cl. 113—1)

This invention relates to improvements in can closing machines and has reference in particular to machines of that character whereby the top ends, or covers are assembled with and seamed to the can bodies after the latter have been filled.

The principal object of the present invention is to provide a machine of the above character that is designed for operating at a high rate on high filled cans, and which will time the filled cans for delivery into the machine, apply the ends thereto, clinch the ends on the bodies and then double seam them; this being accomplished in a manner that avoids spilling of contents from the cans.

More specifically stated, the objects of the invention reside in the provision of a can closing and seaming machine of the above stated character comprising in combination, means designed for taking up the filled cans supplied thereto in a promiscuous, untimed order and for feeding them in a properly timed order into the machine; means synchronized with the timing mechanism whereby the ends are applied to the cans in a relatively slow and easy manner which pushes the contents down into the cans without spilling; a clincher which secures the ends to the body flanges; and a double seamer which receives the cans from the seamer and hermetically seals them; the machine embodying mechanism whereby the filled cans, after being initially received, are moved at a gradually accelerated speed up to the relatively high speed of the clincher mechanism without any irregularity or unevenness of movement that would cause spilling of their contents before application and clinching of the can ends thereonto.

Another object of the invention is to provide a multiple spindle seamer mechanism of novel construction in which each spindle accomplishes what heretofore generally was required to be done by two separate spindles; that is, a multiple spindle machine in which each spindle embodied both the first and second operation seaming rolls.

Still another object of the invention resides in the means provided for accelerating the movement of the cans as they pass from the receiving point to the seamer.

Other objects of the invention reside in the details of construction of the various devices, in their combination and in their mode of operation as will hereinafter be described.

In accomplishing the objects of the invention, we have provided the improved details of con-

struction, the preferred forms of which are illustrated in the accompanying drawings, wherein—

Figure 1 is a perspective view of a can closing and seaming machine embodied by the present invention.

Figure 2 is a top, or plan view of the same.

Figure 3 is a side elevation, opposite that shown in Figure 1.

Figure 4 is a horizontal section particularly showing the path of the cans as advanced through the machine.

Figure 5 is a plan view of the gear train whereby the various operating mechanisms are driven and synchronized.

Figure 6 is a vertical cross section on line 6—6 in Figure 5.

Figure 6a is a detail of parts associated with the control lever and automatic stop mechanism.

Figure 6b is a sectional detail of the same.

Figure 7 is a vertical cross section taken on lines 7—7 in Figures 4 and 5.

Figure 7a is a horizontal section on line 7a—7a in Figure 7.

Figure 8 is a vertical cross section on line 8—8 in Figures 2, 4 and 5.

Figure 8a is a front view of the marking dies.

Figure 8b is a section on line 8b—8b in Fig. 8a.

Figure 9 is a central, vertical section lengthwise of the machine substantially on line 9—9 in Figure 2.

Figure 10 is an enlarged detail of the can feed turret and timing mechanism; parts being broken away for better illustration.

chine in the event no cover is delivered for a can.

Figure 20 is a plan, diagrammatically showing the "no can—no top" control mechanism.

The present machine has been designed primarily for high speed operation, that is capable of closing from 200 to 250 cans per minute, as distinguished from the ordinary types of machines capable only of closing from 100 to 125 filled cans per minute. Heretofore, the speed of operation of machines for this purpose has been limited to a great extent because high filled cans will loose or spill part of their contents if moved too fast, or if the covers are applied to the cans too quickly, and also because of the general use of stationary seamers employing a two stage seaming operation required that the cans be delivered to one station for the initial seaming operation and then to another for the final operation, thus requiring an intermittent moment which slowed up the speed of operation.

In the present instance these disadvantages which have heretofore limited the speed of operation, and which are inherent in machines using the stationary, two stage seamer, and resultant also from overfilling the cans, have been overcome by the employment of a clincher device that easily and slowly applies the ends to the cans while they are moving at a relatively slow speed, so that they may then be accelerated to that of a high speed seamer, which operates to seal the cans without any interruption in their travel and completes both the first and second seaming operations without changing them from one spindle to another.

The employment of the present high speed, revolving seamer has necessitated the use in connection therewith of certain means whereby the advance movement of the filled cans, received in a promiscuous untimed order, may be accelerated from that at which they are received, to that of the clincher which applies and initially secures the ends in place, and by so securing the ends, makes possible a continued acceleration of speed of travel of the filled cans, whereby they are brought up to that of the seamer, without spilling. It has required also the employment of means for accurately timing the delivery of the cans from one mechanism to that following, and it is also in the construction and operation of these timing and accelerating devices, in combination with a double seamer of novel construction, that the present invention resides.

It will be mentioned here that the cans to be operated on are of that type having a peripheral end flange and the covers or ends are provided with a counter sink adapted to fit down within the can and with a flange for overlying the can body flange. The seaming mechanism employed is of that type which seams the flanged peripheral edge of the can end to the outturned flange at the end of the can body; the seam being formed by two operations; the first operation, rolling the flanges more or less loosely, and the second operation tightening and flattening the seam.

In its general construction, as disclosed best by Figures 1 and 2, the machine comprises a can receiving and timing mechanism A; a can end feeding mechanism B; an end marking mechanism C; a clincher mechanism D whereby the ends are applied to and clinched onto the bodies; and a seamer mechanism E; these several mechanisms being arranged to receive the cans suc-

cessively as advanced from one to the other by the action of revolving turrets.

Referring to Figure 4, which discloses in plan view the relationship of the various devices, 1 designates filled cans, and 2 is a traveling belt conveyor on which they are delivered to the machine in an irregular, untimed order onto a horizontal, revolving disk 3 and are here properly spaced and timed in their delivery into the machine by the action of a revolving worm or spiral 4. A revolving feed turret 5 receives the cans from the disk 3 and advances them at an accelerated speed into the regularly spaced pockets 6a of a revolving clincher head turret 6. While the filled, but uncovered cans 1 are being delivered by the turret 5 to the clincher, the can ends, or covers 7, are fed one at a time from a supply stack as will presently be described and are delivered by a turret 8 and applied, one to each of the cans as the latter are delivered successively to the clincher head turret. The cans, with the ends thus applied, are carried through the clincher mechanism and the ends are by its action fixedly attached to the can bodies. On leaving the clincher mechanism the cans are taken up by the radial arms 9a of a revolving turret 9 and are delivered at an accelerated speed to the double seamer mechanism which, in this instance, is a four spindle, revolving mechanism so arranged that successive spindles receive the cans as they are delivered successively from the clincher. A revolving turret 10 extracts and discharges the sealed cans from the seamer onto a delivery belt 11 which carries them from the machine.

A properly synchronized driving connection between the several operating mechanisms disclosed in Figure 4 is provided through the various driving gears and shafts shown in plan view in Figure 5, wherein—15 designates the main drive shaft of the machine. This shaft extends horizontally and transversely through the machine within suitable supporting bearings as in Figure 6, and is provided at one end with a driving belt wheel 16. Keyed on the shaft, within the housing 120 of the machine is a small, bevel gear 17 which drives a larger bevel gear 18 that is keyed on the upper end of a vertical shaft 19. Shaft 19, at its lower end, has a gear wheel 20 fixed thereto and this is in driving mesh with a larger gear 125 21 fixed to the lower end of a vertical shaft 22. A small gear 23 is keyed on the upper end of the shaft 22 in driving mesh with a large gear 24 keyed to a vertical shaft 25 which supports and drives the turret 9 which, as previously stated, 130 transfers the cans from the clincher to the seamer. Gear 24 meshes with and drives a gear wheel 26 which, as will later be described, rotates the seamer head, and this gear 26, in turn meshes with and drives a gear 27 fixed to the lower end 135 of a revolvably mounted vertical shaft 28 which, at its upper end mounts the delivery turret 10 whereby the sealed cans are delivered from the clincher onto the belt 11. The gear wheel 21 also meshes with a smaller gear wheel 29 disposed coaxially below gear 26 and this is keyed to the central, vertical shaft 30 of the seamer mechanism, which, as presently described, drives the several seamer spindles.

Keyed to the upper end of shaft 25 is a gear 145 32 meshing with and driving the main drive gear 33 of the clincher mechanism. This latter gear 33 is of double width and at one side has the spaced but overlapped gears 35 and 36 in mesh therewith. Gear 35 is keyed to the lower end of 150

5 a shaft 37 which, at its upper end, mounts a half mold, or can shaping turret 38. This has pockets 38a designed to be brought into complementary registration with the pockets 6a of the 10 clincher turret 6 to embrace and round up the can bodies preparatory to application of the covers or ends. Gear 36 is keyed to a vertical shaft 40 which, at its upper end mounts the feed turret 5. A gear wheel 41 is also keyed to shaft 40 and 15 this meshes with and drives a gear 42 fixed on the lower end of a vertical shaft 43 which mounts and rotates the feed disk 3.

20 Manual control of the machine, in so far as its starting and stopping operation is concerned, 15 is provided for by an upright hand lever 44 fixed to and supported by a shaft 45 revolvably contained in a supporting bracket 46 fixed to the base housing of the machine, as shown in Figure 3. This control lever has pin and slot connection 25 44a with a collar 47 fixed on one end of a shaft 48 that is extended coaxially through the tubular shaft 15 and at its end opposite the lever is operatively connected with a clutch mechanism 49 associated with the pulley wheel 16. Inward movement of the lever 44 is designed to release the clutch to stop driving of the machine and its outward movement is designed to set the clutch to effect a driving connection between the belt wheel 16 and the shaft 15. A brake disk or cone, 30 as at 50, is fixed to the collar 47 adjacent the control lever, and this is actuated from and into frictional contact with a brake drum 50' fixed to the frame, in accordance with movement of the lever for starting and stopping the machine.

35 The various mechanisms embodied in the present machine are mounted upon a base casting 55. On this, at one end, is secured a housing 56 provided with an extension 56a overlying the other end portion of the base. The housing 56, 40 and the extension thereof, encloses the various driving gears and connections as disclosed in Figure 5, and serves generally for the support of the seamer, clincher, marker and feeding devices, as well as providing the necessary bearings for 45 the various shafts, as will be apparent by reference to Figures 6 to 9. At one end of the extension 56a is secured a housing 57 formed with suitable bearings, 57a for the vertical shaft 43 and serving as a support for the feed disk and timing spiral. The feed disk 3 and the housings 55 and 56a have top surfaces in the same horizontal plane so that the cans delivered through the machine may be slid thereon by the various turrets, in their travel from the feed disk to the clincher and finally to the seamer.

50 A detailed description of the construction and operation of parts in their order from the feed disk to the seamer is as follows: The feed disk 3 is circular and is fixed to the upper end portion of the revolvably driven, vertical shaft 43, which, 55 as shown in Figure 9, is revolvably contained in the vertical bearing 57a formed integral with the casting 57. The upper end of this shaft extends slightly above the top of the disk and mounts a cam plate 61 of circular form but of lesser diameter than the disk and which is fixed against rotation as shown in Figures 4 and 10, by its attachment, through the medium of a bolt 62, to a can guide 63; the latter being rigidly supported by an end portion thereof that overlies and which is fastened to the top of the housing 56a by bolts 64. The filled cans 1, delivered to the machine on the belt 2 generally pass onto the feed disk 3 in an irregular, untimed order and 70 against a guide flange 65 at the receiving side

of the disk along which they are carried into contact with the timing spiral 4. This spiral is revolvably supported at its opposite ends in bearings 67 and 68, and, at one end, as shown in Figure 10, has a gear 69 fixed thereto in mesh with a driving gear 70 keyed on the upper end of a vertical shaft 71, which is driven, as shown on Figure 5, by a sprocket chain belt 72 operating about sprocket wheel 73 on the lower end of the shaft and a sprocket 74 on a shaft 75. A gear 76 is fixed to shaft 75 in mesh with the driven gear 42 on shaft 43. The lower end of shaft 71, and also shaft 75, are revolvably mounted in suitable bearings provided in a lateral extension 57' integral with the casting 57, as shown in Figure 1.

80 The cans 1 by engaging the thread of the spiral 4, are properly spaced for delivery into the machine and on being released by the spiral, are carried into a can guideway that is formed by the guide flange 63 and a parallel flange 78 that is fixed to the top of the casting 56a. The advancing means consists of feed fingers 80 carried by the disk 3 and which operate to move the cans at an accelerated speed into the successive pockets 5a of the feed turret 5.

85 In order that the cans on entering the machine may be held yieldingly against the timing spiral 4, but will not be dented thereby in the event that one becomes centered on a thread of the spiral, 90 we have provided a presser shoe 81 that lies substantially parallel with the spiral and which is pivotally mounted by a stud 82 fixed in the top of the cam plate 61. The free end of the shoe is curved to permit cans on entering to pass between it and the spiral. Inward travel of the shoe is limited by reason of one end engaging with a set screw 83 mounted in a boss 84 on the cam plate, and it is retained yieldably against outward movement by reason of the pressing thereagainst of a counter weight lever 85, as in Figure 12. This lever is pivotally mounted on a bolt 86 fixed in a boss 86' on the cam plate with a weight 86a adjustable along the lever to vary the retaining pressure against the shoe. With 100 this arrangement, the cans 1 pass to the timing spiral between the swinging end of the shoe 81 and the guide flange 65. Should a can become centered on a thread of the spiral, the shoe will yield outwardly to prevent any damage being 105 done to the can body but will urge the can against the spiral so that it will be taken up and advanced by the next thread of the spiral.

110 Referring to Figures 10 and 11, it is to be seen that the feed disk 3 has a lowered central portion provided with bosses 87 at regularly spaced intervals circularly about the axis of the disk, in which studs 90 are mounted. On each stud is pivotally mounted a finger 80 provided at one side with an inward extension 80a mounting a 115 roller 91. These rollers are adapted to follow within a cam groove 92 formed in the under side of the cam plate 61 in such manner that, as the feed disk 3 rotates, the rollers 91 following along the groove will cause the fingers to swing 120 outwardly to engage the cans after they are spaced apart by the timing spiral, and to push them along into the pockets of the accelerating turret 5 after which the fingers are then moved inwardly by the cam so as not to interfere with 125 the passage of oncoming cans to the timing spiral 4. The outer ends of the fingers 80 are properly curved to conform to the curvature of the cans. On being picked up by the feed turret 5, the cans are moved with an accelerated speed to the 130

clincher mechanism, and to obtain this accelerated movement of the cans after leaving the timing spiral to bring them up to the angular speed of rotation of the feed turret 5, the can guideway provided between the guide flanges 63 and 78 gradually increases in radial distance from the center about which the feed fingers and disk 3 revolves, and this increase causes an acceleration in the speed on the cans as they are advanced along the guideway by the feed fingers 80. The timing of the parts is such that the cans are delivered into the pockets of the turret 5 at the same angular speed of the turret.

The clincher mechanism, as best disclosed in Figures 2, 9 and 13, is a six spindle arrangement revoluble about a tubular supporting standard 100 fixed vertically upon the housing 56a. A table 101 is revolvably mounted about the base portion of the standard and it is rotated by the ring gear 33 that is fixed coaxially thereto. Carried by the table, at regularly spaced intervals circularly about the standard, are the can pads 102 in exact registration below the pockets 8a of the turret 6, and onto which the cans are delivered by the turret 5. Each pad is supported revolvably, through the intermediary of anti-friction bearings 103, about a bearing 104 that is fixed to the table by a bolt 105. The pad is permitted a slight vertical travel on its spindle and is urged upwardly and is yieldably held against a peripheral end flange 106 of the bearing by coiled springs 107 which are contained in sockets 108 in the table to press upwardly against a disk 109 on which the bearings rest. Downward movement of the pads when under pressure, is limited by the disk being brought against the table.

Supported revolvably about the upper end of the standard 100 and revolvably driven from the table 101 through the intermediary of the turret 6, is a head 110 in which spindles 112 are revolvably mounted; these spindles being coaxially aligned with the pads 102. Each spindle is revolvably mounted within a supporting slide or guide sleeve 113 and the sleeves all are vertically slidably in the head and are adapted to be actuated upwardly and downwardly as the head revolves about the standard by a cam 114.

The cam 114, as shown in Fig. 13, is held against rotation on the standard 100 by a sliding keyed connection as designated at 114b, and has supporting connection with a gear 116 mounted on the standard directly above it. The gear 116 has an elongated hub portion 117 slidably keyed to the standard and the gear in turn is supported by a connection with a nut 118 threaded onto the upper end of the standard; this connection consisting of arcuate keys 118a that are seated within an annular groove 118b in the upper end of the gear hub and which are clamped against the upper face of the groove by a plurality of bolts 118c which are extended through the nut and are threaded into the keys.

The connection between the gear 116 and cam 114 provides for vertical adjustment of the latter on the standard and the connection consists of a bolt 115 rotatably mounted in a sleeve 115a threaded through the gear. The bolt's are threaded into the upper end flange 114a of the cam to support it and the sleeves 115a are headed and may be rotated to effect the vertical adjustment.

The cam 114 has an encircling cam groove 120 within which rollers 121, carried by studs 122 fixed in the sleeves 113, are adapted to follow to raise and lower the spindles as the head revolves.

As was previously stated, the can ends 7 are delivered to the clincher by a feed mechanism,

presently described in detail, including the turret 8, and as they are delivered, they are picked up by chucks 124 that are mounted at the lower ends of the spindles 112. After being picked up by the chucks, the ends are pressed thereby onto the cans as the latter are delivered to the clincher turret by the turret 5. The cam groove 120 is so formed that each spindle and its chuck will be in an elevated position at the time a can enters the turret beneath it but will immediately thereafter be lowered to press the cover or end onto the can and hold it during the following clinching operation which curls the flange of the end downwardly beneath the peripheral flange of the can body sufficiently to hold the end in place, as is shown in Fig. 13a. A feature of this construction resides in the formation of the cam groove 120 which causes the can ends to be moved down easily and slowly against the can end and seated therein so that the heaped up contents in high filled cans will be pressed down into the cans without any resultant squashing out or spilling.

The can end feed mechanism operates to deliver the can ends 7 to the chucks as the clincher head revolves and the chucks then operate to place the ends on the cans and hold them there for the clinching operation. The feed mechanism is best shown in Figures 2, 3, 7 and 8, and is supported by a bracket 125 that is fixed to one side 105 of the housing 56a by a plurality of bolts 126 in such manner as to permit of vertical adjustment. This bracket has a flat top surface 125a on which a hopper or guide 127 is mounted. The can ends 7 are stacked in this hopper and are fed from its lower end, one at a time, into the pockets 8a of the intermittently revolving turret 8 by the reciprocal action of a feed slide 128 that operates in a guide provided therefor in the bracket top. The reciprocal action of the feed slide is produced through its connection by a link 129 with one end of an arm 130 fixed to a vertically mounted shaft 131; the shaft being mounted at its upper end in a bearing 132 fixed to the bracket 125 and, at its lower end, in a bearing 133 extended from a gear casing 134 fixed to the housing 56, and it is oscillated through the medium of a connecting link 135, which is pivotally attached at one end to an arm 136 mounted on the shaft in a manner later described, and at its 120 other end is connected with a crank 138 fixed on a short, vertical shaft 139 mounted revolvably in a bearing 140 at one side of housing 56 and driven by a gear 141 keyed thereto in mesh with the driven gear 24, as shown in Figure 5 and in 130 Figure 6.

The reciprocal action of the slide delivers the can ends into the pockets of the turret 8 and rotative movement of the turret carries them directly and closely beneath the chucks 124 as the clincher head rotates and they are picked up by the chucks and are held centered thereagainst, ready for application to the cans, by an application of vacuum to the under sides of the chucks.

The intermittent movement of the feed turret 140 8 is produced as follows: The turret is mounted on the upper end of a vertical shaft 142 mounted in bearings 143—143', as shown in Figure 7. At its lower end is a driving gear 144 which has connection with an intermittent gear 145 fixed to the 145 lower end of a vertical shaft 146 mounted in bearings 147—147'. A small driving gear 148 is keyed to shaft 146 and this meshes with the gear wheel 36. Through this connection the can end feed turret 8 is intermittently moved so that its 150

pockets successively receive the ends advanced by the feed slide, then carry them into position for marking, then to the clincher which picks them up during an advance movement of the turret.

5 It will here be stated, that the intermittent gear mechanism which advances the turret 8 is such that the turret carries the can ends at the same rate that the spindles of the clincher are rotating so that they may be picked up by the clincher chucks without interference when vacuum is applied to the latter.

10 Vacuum is applied to the chucks as follows: Each spindle, as shown in Figure 13, has an axial channel 150 communicating at its lower end with the under face of the chuck, and has a sliding connection at its upper end with a tube 151 projected into the channel and connected with a header 152 that is revolvable with the head 110 about the gear 116 that is fixed adjustably to the 15 standard 100. A valve collar 153 encircles the gear hub and is fixed against rotation and has an airtight fit with the header. A pipe 154 leading from a source of vacuum connects with an annular channel 155 in the valve collar and this 20 communicates through outlets 156 with channels 157 in the header leading to the various tubes 151. The outlets 156 are so located and so designed that the valve operates to apply the vacuum while the spindles are traveling through that 25 certain arc where it is required that the ends be picked up and carried to the cans.

30 Application of vacuum to the chucks causes the ends to be picked up and held tightly against the chucks as the latter moves into registration with the filled cans delivered by the turret 5. The cam 114 then causes the spindles to move downwardly to press the ends 7 tightly within the can body flanges.

35 After the ends are thus applied to the cans, the clinching operation starts. This is effected by advancing the flanged peripheral edges of the ends in rolling contact with a clincher ring segment 159 that is supported, as shown in Figures 4, substantially concentrically of the clincher 40 head and standard 100. This clincher ring segment is supported within a seat 160 formed along the top edge of an arcuately curved support 161 that is rigidly mounted by a pair of supporting posts 162 and 163. The ring segment 159 has a 45 curling groove 159a along its inner edge for receiving the periphery of the can end in rolling contact therewith to turn the flange inwardly beneath the can body and flange, as shown in Figure 13a. The segment is adjustably mounted, 50 and is held on its support 161 by overlying clamps 165 fixed by bolts 166 to the support and it may be adjusted inwardly or outwardly to curl the flange to the desired extent.

55 To insure the desired clinching operation, it is required that the cans be revolved while moving along the clincher ring segment and not allowed to merely slide along it, since this would not effect the desired curling of the flange. To cause the cans to revolve, the chucks and their spindles are revolvably driven and since the chucks are pressed tightly against the cans, this causes them to revolve. The means provided for revolving the chucks, as shown in Figures 2 and 13 wherein 60 167 designates gears fixed to the upper ends of the spindles and meshing with idle gears 168 mounted on the head 110 and in mesh with the gear 116. The gears 168 are carried by spindles 169 and are relatively long so as to permit of the up and down movement of the spindles without 65 disconnection.

70 On leaving the end of the clincher ring segment, the cans, with ends attached thereto, are picked up by the radial arms of the turret 9 and are advanced along a guide flange 170 to the seamer mechanism; the guide 170 being eccentric 75 or the turret so that the cans will be advanced at an accelerated speed and delivered exactly into registration with the spindles of the seamer.

80 The seamer mechanism, as shown best in Figures 1, 9 and 14 is a four spindle mechanism wherein each spindle performs a complete seaming operation; that is, it embodies both the first and second operation seaming rolls, usually carried by two separate spindles. The mechanism, 85 as shown in detail in Figures 9 and 14, comprises the can pad table 175 fixed to a central tubular supporting post 176 revolvably mounted in a vertical position within bearing members 177-178 within the housing 56; there being anti-friction bearings 179 revolvably mounting the post. The 90 table is revolvably driven through the mediacy of the gear 26 which is keyed to the lower end of the post and which in turn is driven through the gearing previously described, and shown in Figure 5. Mounted by the table at equally spaced 95 intervals about its axis, are the pads 182 onto which the cans are delivered by the turret 9 upon leaving the clincher mechanism. Each pad is mounted by a shank 183 extended downwardly therefrom onto a slide 184 mounted within a 100 guide bushing 185 fitted within a bearing 186 formed as a part of the table 175. The shank has a cross key 187 fixed on its lower end and this is slidable at its ends in a slot 188 in the slide to permit of a slight raising and lowering of the 105 pad while held against rotation. The slide in turn is held against rotation by a key 189 fixed to its lower end and slidable in a key slot 189a in a flange 175a depending from the table. (See Figure 14.)

110 Threaded onto the upper end of the shank is a nut 190 having a sleeve portion 190a slidable in the upper end of the slide 184 and a coiled spring 191 bears against the lower end of the nut sleeve and against a shoulder 192 in the slide, to 115 yieldably hold the pad in a raised position. Upward and downward adjustment of the nut varies the tension of the spring and the nut is adapted to be locked where adjusted by a yieldable latch 193, carried by a flange 194 fixed to the under 120 side of the pad, and engageable with grooves 194' in the periphery of the nut.

125 At its lower end the slide carries a roller 198 mounted by a pin 199 for rolling contact with a cam ring 200 encircling the post and, preferably, 130 being an integral part of the bearing 177. This cam is so formed as to permit lowering of the pads, as the table rotates, to proper elevation for receiving the cans thereon from the clincher mechanism, then to raise them upwardly to bring 135 the top ends of the cans into proper relation to the seaming spindles for seaming. To insure lowering of the pads a roller 202 is mounted by the outer end of pin 199, as shown in Figure 14, 140 and a cam segment 203 is fixed to the housing 56 to engage therewith to pull the slides downward to withdraw the cans from the seaming spindles.

145 The four seaming devices are revolvably mounted in a seamer head 210 fixed to the upper end of a supporting and driving sleeve 211 which has its lower end portion slidably keyed, as at 212, within the upper end portion of the tubular post 176. Each seaming device comprises a spindle 215 coaxially aligned with one of the can mounting pads, and revolvably supported through the me- 150

diacy of upper and lower sets of ball bearings 216 and 217 fitted within the seamer head; the lower bearings being supported by a bottom plate 218 fixed by bolts 219 to the under side of the seamer head 210 and the upper bearings are supported on the upper end of a collar 220 that is fitted about the spindle and which rests at its lower end on the inner raceway of the lower set of bearings. A driving gear 222 is keyed on the upper end of each spindle and are locked against the inner raceways of the upper sets of bearings by nuts 223 threaded onto the upper ends of the spindles. The several spindles are revolvably driven through their gears 222 which mesh with a central gear 225 that is keyed to the driven shaft 30 which extends centrally through the post 176 and sleeve 211 and which is revolvably driven, as previously described, by the gear 29 fixed to its lower end. This shaft 30 is revolvably mounted at its lower end by bearings 226 fitted within the lower end of post 175, and at its upper end by bearings 227 carried in the upper end of a sleeve 228; this latter sleeve being fitted about the shaft and fixed at its upper end to an arm 230 which, as shown in Figure 9, is mounted on the upper end of the standard 100 about which the clincher head revolves. This arm serves not only as a brace for the seamer but also prevents rotation of the sleeve 228 and certain parts associated therewith.

Directly after the cans are delivered onto the seamer table pads 182 from the clincher mechanism, the pads are actuated upwardly to press the top ends of the cans against the seamer chucks 235 which are carried at the lower ends of shafts 236 extended coaxially through the seamer spindles and locked at their upper ends by nuts 237 in a head 238 that is revolvable with the seamer head; this head 238 having a hub portion 238' whereby it is revolvably mounted about the upper end portion of a cam 240 that is mounted about the lower end of the sleeve 228 above the gear 225, but which is held against rotation by a keyed connection as at 241 with the sleeve.

After a can has been lifted by the pad on which it rests, against the chuck 235 of the seaming mechanism, the seaming operation takes place. For this operation each spindle is provided with an enlarged head portion 215a at its lower end in which is mounted a pair of slide bars 250—250', horizontally slideable in parallel relation at opposite sides of the shaft 236, as shown best in Figures 14 and 17.

The bar 250 is provided, at one end, on its upper side with paired lugs 251, and the slide bar 250' is likewise provided at the opposite end, with lugs 251'. The slides are actuated by toggle links 252—252' of an S-shaped formation to permit of a certain amount of yielding when the seaming rollers pass over the can side seam, and which have their outer ends pivotally attached, as at 253 between the lugs, and have their inner ends pivotally attached by pins 254 to a member 255 that is located within the spindle and which is fixed to the lower end of a sleeve 256 which extends upwardly from the seamer head. At the upper ends the sleeves 256 of the several spindles have cam rollers 258 mounted thereon and these follow within the groove 240' of cam 240 so that, as the seamer head revolves, the sleeves and the members 255 are moved upwardly and downwardly within the spindle heads.

Mounted on the under sides of the slide bars, and at opposite ends, as shown in Figures 17 and 18, are seaming rolls 260—260, designated as the

first operation rolls. Likewise mounted at the opposite ends of the bars, are seaming rolls 261—261, designated as the second operation seaming rolls. These are circumferentially grooved in the usual manner for the double seaming operation, and are at the proper level with respect to the chucks 235 to cooperate therewith.

When a can is lifted against its chuck 235, the member 255 is in neutral position and the seaming rolls are retracted sufficiently from the chuck to permit the engagement of the can with the chuck; then, as the seamer head revolves, the cam 240, through its connection with the sleeves 256, causes the sleeve to be shifted upwardly. This draws inwardly and upwardly on the toggle links and causes the slide bars to be so moved as to bring the first operation seaming rolls against the can end flange to effect the initial seaming operation. Then the sleeves are actuated downwardly so that the toggles move the slides in the opposite direction and bring the second operation rolls against the can flange to complete the seaming operation. Then the sleeve is lifted to bring the slides and rolls back to neutral position.

As soon as a seam is thus formed, the pad 182 on which the can rests is lowered and the can is pushed loose from its chuck 235 by a pusher rod 265 which extends coaxially through the chuck mounting shaft 236 and which has a head 266 at its lower end and a head 267 at its upper end adapted to engage with a cam 268 carried by an arm 269 fixed to the brace bar 230 so as to push the rod downwardly at the proper time. The cans are then taken up by the arms of turret 10 and delivered from the machine.

It is preferred that the seaming rolls be adjustably mounted in their slides so that they may be adjusted to suit different sizes of cans, and for this purpose each roll is mounted, as shown in Figure 15, on a carrier 275 that is slideable in a longitudinal groove 276 in the slide bar. An adjusting screw 277 is threaded through each block and has a rotatably fixed connection with the bar, as at 278, so that by turning the screw, the carrier 275 will be moved lengthwise of the bar.

Certain adjustment is also provided for in the seamer for adjusting the head to accommodate cans of different length. As shown in Figure 14, the sleeve 211 which supports the seamer head above the can pad table 175 has a threaded portion 280 about its lower end portion and a nut 281 is mounted thereon within the upper end of post 176 to support it. A worm 282 meshes with the nut and this has an end portion 283 to which a wrench may be applied to rotate the nut as a means of raising or lowering the head with respect to the table.

The means employed for applying identification marks to the can ends is associated with the can end feed mechanism, and is shown best in Figures 2, 8a and 8b. As shown in Figure 8a, there is a lower die holder 290 of six faces mounted rotatably on a stud 291 fixed in the bracket 125 directly below the path of can ends delivered by the turret 8 from the supply stack and also registering directly below one of the pockets 8a in the turret when the turret is at rest. Mounted on a vertical slide bar 292 that is slideably contained in a groove 293, in a bracket 126a fixed above the turret 8, is an upper die holder 294 rotatably mounted on a pivot stud 295 fixed in the bracket 126a directly over the die holder 290. These die holders carry complementary dies adapted to engage opposite faces of the can ends 7 to impress the mark. To change the mark, it is only necessary to rotate the die holder 294.

sary to rotate the die holders to bring other faces into position. The die holders are held at adjusted positions by latches 290a carried in the studs to engage notches 290b in the holders. A lever 296 is pivotally attached to the slide by bolt 297, and is pivotally attached by a link 298 at one end to the bracket and at its other end is attached to a link 299 connected to a revolving crank 300 whereby the lever is oscillated to cause the upper die to be actuated downwardly against the can ends, as delivered by the turret, directly against the lower die to thereby apply the die mark.

The crank 300 is fixed to one end of a short shaft 301 mounted in a bearing 302, as shown in Figure 5, and the shaft is rotatably driven by a bevel gear 303 fixed thereon and meshing with a bevel gear 304, see Figure 6, on the vertical shaft 139 which operates, in connection with parts previously described, to actuate the can end feed slide mechanism. The timing of these parts is such that the mark is applied to the can end while it is at rest.

The means provided for automatically stopping the machine in the event the can end supply becomes exhausted, or should a can end fail to be delivered for any reason, is shown in Figures 4, 6, 6a, 6b, and diagrammatically in Figure 19. As shown best in Figures 3 and 6b, the main control lever 44 for starting and stopping the machine is mounted on a shaft 45 rotatable in the supporting bracket 46. At one end of shaft 45 is an arm 320 rigidly fixed thereto and adjacent this arm is an arm 321 that is adapted to be oscillated through its connection by means of a link 322 with a crank 323 on the driven shaft 301, as is illustrated in Figure 6a. The arm 320 has a trigger 325 pivotally mounted thereon, as at 326, with its upper end extended across the end of shaft 45 and its lower end disposed in a position to be moved into and from the path of travel of the oscillating arm 321. A push rod 328 extends coaxially through shaft 45 and at one end bears against the upper end of trigger 325, and with its other end is engaged by one arm 330 of a bell crank on a pivot 331; the other arm 332 of the crank bearing against the upper end of the core 334 of a solenoid 335 mounted by a bracket 336. The arrangement is such that whenever the solenoid is energized, its core is lifted upwardly, thereby rocking the bell crank and pushing rod 328 inwardly to rock the trigger 325 to cause its lower end to swing inwardly to a position at which it is engaged by the oscillating arm 321. This causes the lever arm 320 to be moved therewith and the shaft 45 to be rotated in such manner as to cause the lever 44 to be thrown inwardly to stop the machine. Energization of the solenoid is under control of cans and ends delivered to the machine as shown in Fig. 19, wherein 338 designates a switch box supported from the bracket 125 and containing a yieldable switch lever 339 movable by rotative movement of a cam 340 from and against a contact 341. The cam is mounted on a shaft 342 supported vertically in the bracket and having an arm 343 at its lower end adapted to be engaged and moved by cans passing from the feed turret to the clincher. The passing of each can causes the cam to be resolved to thereby permit the switch arm to rest against the contact 341.

Likewise, there is a switch box 348 mounted beneath the can end feed turret, as shown best in Figure 7, and this also contains a yieldable arm 350 normally engaging a contact 351, but adapted to be disengaged therefrom with each deliv-

ery of a can end across the upper end of a plunger 352 which rests on the arm and has a head position projecting into the path of can ends delivered by the turret 8.

As shown diagrammatically in Figure 19, the switch lever 339 has a wire connection 353 with arm 350, and switch contact 351 is connected to one side of the solenoid by wire 354. The other side of the solenoid connects by wire 355 with a source of electricity, as at 356, and a wire 357 connects the other side of said source with the switch contact 341. With this arrangement, the circuit through switch box 338 is normally open but is closed by the passing of a can. The circuit through switch box 348 is normally closed, but is opened by the delivery of a can end across it. The delivery of cans past lever 343 is so timed with the delivery of covers below the switch box 348 that the switches cannot both be closed at the same time so long as both are feeding in proper order, however, should a can end fail to be delivered, this results in a circuit being closed through the solenoid and a consequent stopping of the machine. The can actuated switch is necessary, for without it, the circuit would be closed each time a cover was advanced from the switch 348.

The mechanism for preventing delivery of a can end in the event no can is being delivered to receive it, is shown diagrammatically in Fig. 20, wherein 360 designates an arm mounted at the upper end of a vertical shaft 361 at the side of the guideway through which the cans are delivered from the feed disk to the clincher. This arm projects into the can path and is adapted to be engaged by each passing can to give the shaft a rotative movement. At the lower end of the shaft is an arm 363, connected by a link 364 with a pivoted pawl 365 which is adapted to be moved from and into the path of movement of a latch 366, that is mounted on the arm 136 through which the shaft 131 is oscillated to actuate the can end feed slide. Referring to Figure 20, it is seen that the shaft 131 has an arm 370 keyed thereto and this bears against a stop lug 371 on the lever 136 and is normally held in that position by latch 366 so that oscillation of the lever 136 by rod 135 causes action of the feed slide.

In the event a can is not delivered to the machine, the lever 360 swings inwardly by reason of the pull of spring 374 attached to arm 363, and this causes pawl 365 to swing into the path of latch 366 and to engage and release the latch from the arm 370 so that the lever 136 oscillates freely on the shaft 131 and no end will be fed to the machine. As soon as the delivery of cans is resumed, the pawl is withdrawn and the end feeding action is resumed by reason of the latch 366 snapping back over the end of arm 370.

Having thus described our invention what we claim as new therein and desire to secure by Letters Patent, is:

1. A can closing machine comprising a series of continuously traveling seaming units, a clincher including a series of continuously traveling can carriers, devices for receiving cans and for timing and delivering them to the traveling carriers of the clincher mechanism and devices for receiving cans from the carriers for feeding them to the seaming units.

2. A can closing machine comprising a series of continuously traveling seaming units, a clincher mechanism including a series of continuously traveling can carriers, devices for receiving cans

- fed thereto promiscuously and for timing and delivering them successively to the traveling can carriers of the clincher, and devices for receiving the cans from the carriers and for delivering them without stop successively to the seaming units. 5
3. A can closing machine comprising a seaming mechanism including a series of seaming units continuously moving at high speed about a common axis, a clinching device including a series of units continuously rotating at a slower speed about a common axis, devices adapted to receive filled cans delivered in promiscuous order and to space and deliver them at a gradually accelerated speed successively to the clincher units and devices for receiving the cans successively from the clincher units and to deliver them at a gradually accelerated speed to the successive units of the seaming mechanism. 10
4. A can closing machine comprising a seaming mechanism including a series of spaced, continuously traveling seaming units, a clincher mechanism including a stationary rail and a series of spaced, continuously traveling units for presenting cans successively to the said rail for clinching, devices for receiving filled cans fed thereto promiscuously for timing, spacing and delivering said filled cans successively to the units of the clincher mechanism and devices for receiving the cans from the clincher mechanism for spacing and feeding the same without stop to the seaming units. 15
5. A can closing machine comprising a series of continuously moving seaming units, a series of continuously moving clincher units, devices for receiving filled cans and for delivering them successively to the clincher units, means for assembling covers on the cans as they are delivered to the clincher units and devices for receiving the cans from the clincher units for feeding the same successively and without stop to the seaming units. 20
6. A can closing machine comprising a seaming mechanism including a series of spaced, continuously traveling seaming units, a clincher mechanism including a stationary rail for clinching and a series of spaced, continuously traveling units for presenting cans in succession to said rail, devices for receiving filled cans and for spacing, timing and delivering said filled cans successively to the traveling units of the clinching mechanism, means for delivering can covers to the clincher units, means for causing the covers to be applied to the cans for clinching and means for delivering the cans with covers clinched thereon successively to the units of the seaming mechanism. 25
7. A can closing machine comprising a seaming mechanism including a series of spaced, continuously traveling seaming units, a clincher mechanism including a stationary can rail and a series of spaced, continuously moving units for presenting cans in succession to said rail for clinching covers thereon, a chuck associated with each of said clincher units, devices for receiving filled cans and for timing and delivering them to successive units of the clincher, means for feeding can covers to the chucks, means for causing the chucks to apply the covers to the filled cans for presentation to the clinching rail and means for receiving the cans from the clincher and for delivering them successively and without stop to the units of the seaming mechanism. 30
8. A can closing machine comprising a seaming mechanism including a series of spaced, continuously traveling seaming units, a clincher mechanism including a stationary rail and a series of spaced, continuously moving units for presenting cans in succession to said rail for clinching covers thereon, a chuck associated with each of said clincher units, devices for receiving filled cans and for timing and delivering them to successive units of the clincher, means for feeding can covers to the chucks, a cam associated with the several clincher units for moving the chucks to slowly apply the covers to the filled cans for presentation to the clinching rail and devices for receiving the cans from the clincher units and for delivering them successively and without stop to the seaming units. 35
9. A can closing machine comprising a series of continuously traveling seaming units, a clincher including a stationary rail and a series of continuously traveling carriers for presenting cans to said rail for clinching, means for delivering cans from successive carriers successively to the seaming units, and a can feed mechanism including means for receiving cans promiscuously and for spacing and timing their release, and devices for advancing the successively released cans at an accelerated speed to successive can carriers. 40
10. In a can closing machine, a series of can carriers continuously revolving at a relatively high speed about a common axis, a guideway, and can feeding means comprising a timing screw which receives cans delivered thereto promiscuously and spaces and times their delivery into the guideway, means for taking up the cans as they are released by the screw for moving them along the guideway at a gradually accelerated speed to deliver them successively to the can carriers at the speed of the latter. 45
11. In a can closing machine, a series of can carriers continuously revolving at a relatively high speed about a common axis, and a can feed mechanism including a revolving disk on which filled cans are initially received in promiscuous order, a timing screw which receives, spaces and times the release of the cans for farther advancement by the disk, a can guideway for receiving the cans from the screw having a radially curved portion eccentric of the axis of the disk, and a continuing radially curved portion leading to the can carriers, radially directed pushers mounted by the disk to engage the cans as they are successively released by the screw and for advancing them at a gradually accelerated speed along the guideway, and a revolving transfer turret adapted to receive the cans from the disk to advance them at an accelerated speed and to space and deliver them successively to the revolving can carriers at the speed of the latter. 50
12. In a can closing machine, a can feed mechanism comprising a continuously revolving disk onto one side of which filled cans are received in promiscuous order, a can guideway overlying the disk eccentric thereof, a timing screw which receives the cans delivered onto the disk, and initially spaces and times their release for delivery by the disk along the guideway, and pushers carried by the disk to engage with the cans as they are delivered to the guideway and whereby the cans are advanced at a gradually accelerated speed and their spacing increased accordingly. 55
13. In a can closing machine, a can feed mechanism comprising a continuously revolving disk onto one side of which filled cans are received in promiscuous order, a can guideway 60

5 overlying the disk eccentric thereof, a timing screw which receives the cans delivered promiscuously onto the disk and initially spaces and times their release for delivery by the disk into the guideway, a cam adjacent the disk, a plurality of pushers pivotally mounted by the disk and having cam engaging means whereby they are caused to move into the guideway to engage the cans as they are successively released by the 10 timing screw to advance them therein at a gradually increased speed and to increase their spacing.

14. In a can closing machine, a can feed mechanism comprising a continuously revolving disk onto one side of which filled cans are received in promiscuous order, a can guideway overlying the disk eccentric thereof, a timing screw which receives the cans delivered onto the disk and initially spaces and times their release 15 for delivery by the disk into the guideway, a fixed cam, a plurality of pushers pivotally mounted by the disk and having cam engaging means whereby they are caused to move outwardly to engage the cans as they are successively released by the timing screw to advance them along the guideway at a gradually increased speed and to increase their spacing; said pushers being retracted by the cam from the disk surface at the 20 can receiving side and adjacent the timing screw.

15. In a can closing machine, a series of can carriers continuously revolving about a common axis, a transfer turret for delivering cans successively to the carriers, and a can feed means comprising a horizontally revolving disk, a guideway overlying the disk into which filled cans are delivered, and having a portion thereof eccentric to the disk axis and leading to the transfer turret, a feed screw associated with the guideway for 25 receiving cans from the guideway promiscuously and for spacing and timing their release for further advancement by the disk, a fixed cam, concentric of the disk, a plurality of fingers pivotally fixed to the disk and having cam followers 30 whereby the fingers are actuated inwardly from the guideway at the can receiving side and are actuated outwardly to engage the cans as they successively leave the timing screw and to advance them to the transfer turret with a gradually 35 accelerated movement by reason of the eccentric relation of the guideway to the disk.

16. In a can closing machine, in combination, a series of can carriers revolving continuously about a common axis, means for delivering cans successively thereto, an intermittently revolving turret having pockets therein, means for feeding can covers successively to the pockets during its successive periods of rest; said turret being adapted to carry the covers received through a certain 40 interval in registration with the revolving can carriers and means associated with the carriers operable during that interval for transferring the covers from the turret for subsequent application to the cans.

17. In a can closing machine, in combination, a series of can carriers revolving continuously about a common axis, means for delivering cans successively thereto, an intermittently revolving turret, means for feeding can covers to the turret, a marking device for operating on the covers advanced thereto by the turret during its successive periods of rest; said turret being adapted to carry each marked cover through a certain interval 45 while in registration with a revolving can carrier and means associated with the carriers for lifting

the market covers from the turret and for subsequently placing them on the cans.

18. In a can closing machine, in combination, a series of can carriers continuously revolving about a common axis, means for delivering filled cans successively thereto, a pocketed turret, means for intermittently revolving the turret, means for delivering can ends to the pockets during successive periods of rest, a marking device to which the covers are successively advanced by the turret for marking thereby during succession periods of rest of the turret; successive pockets of the turret being adapted to travel for an interval in registration with the revolving can carriers, and means moving with the carriers for lifting the marked covers from the pockets of the turret and subsequently applying them to the cans.

19. In a can closing machine, in combination, a plurality of spaced clincher units revolving continuously about a common axis, means for feeding filled cans successively to the said units, a reciprocating die for marking can covers, a pocketed turret, means for intermittently revolving the turret, means for feeding can covers successively to the pockets of the turret for advancement by successive advance movements of the turret into position for marking by the die, a chuck associated with each of the can clincher units, and adapted to travel in registration for a definite interval with pockets of the turret, means 100 for applying suction to the chucks during such intervals to lift the marked covers from the pockets, and means for causing the chucks to apply the covers to the cans.

20. In a can closing machine, in combination, a clincher mechanism including a stationary cam rail, a series of clincher units continuously revolving about a common axis for successively presenting cans delivered thereto to said rail, means for delivering filled cans successively to the units, 110 a hopper for containing a stack of can covers, a pocketed turret, means for intermittently revolving the turret to bring the pockets successively into position for receiving covers from the hopper, a reciprocating feed slide synchronized with the 115 turret operating means for delivering covers from the hopper into the pockets as they are successively brought into receiving position, a reciprocating marker to which the covers are successively advanced by the turret and by which they are 120 marked during periods of rest of the turret; each of said clincher units having a chuck associated therewith and said chucks being adapted to travel in registration with the marked covers in the 125 turret pockets for a limited interval, means for causing suction to be applied to the chucks during this interval to lift the covers from the pockets and means whereby the covers are then caused to be applied to the cans for presentation to the clincher rail.

21. In a can closing machine, including a series of clincher units continuously revolving about a common axis, means for spacing and advancing cans in regular order successively to the clincher units, means for feeding can covers successively to the units for application to the cans; said means including a releasable connection, devices for releasing said connection to temporarily discontinue feeding of covers; said devices being normally retained at inactive position by cans being delivered in regular order to the units but permitted to move to active position by reason of absence of a can in regular order of delivery to the units.

22. In a can closing machine, devices for delivering filled cans at regular intervals successively to 150

- the machine, means for feeding can covers successively to the machine for application to the cans; said means including an actuating shaft, an arm fixed to said shaft, a second arm rotatable thereon, a yieldable latch on one of said arms normally connecting it to the other to cause them to move together, a continuously revolving crank, a rod connecting the crank and said second arm for oscillating the shaft, a trip lever adapted to be moved into the path of the said latch to cause the arms to be temporarily disconnected, and an actuating means for said trip lever including an arm adapted to be engaged by cans delivered in regular order to hold the trip lever out of contact with the latch but movable, incident to the absence of a can in regular order, to release the latch to effect non-delivery of a cover in a corresponding order. 23. In a can closing machine, means for delivering filled cans successively into the machine, means for delivering can covers into the machine in accordance with delivery of cans, a driving means for the machine including a releasable clutch, means adapted to be electrically energized to effect releasing of the clutch to stop the machine, an electric circuit for said means, a normally open switch in the circuit adapted to be momentarily closed by the passing of each can to the machine, a normally closed switch in the circuit adapted to be momentarily opened incident to the passing of each cover to the machine; said covers being timed in their delivery to open the latter switch during closed intervals of the first switch and said circuit being adapted to be completed by the first named switch incident to the closed condition of the second switch by reason of non-delivery of a can cover in its regular order. 24. In a can closing machine, the combination with a guideway, and means for delivering filled cans in regular spaced order successively into the machine, an intermittently moving turret having pockets therein, means for feeding can covers into the pockets for delivery by the turret to the machine, a driving means for the machine including a releasable clutch, a solenoid adapted to be energized to effect releasing of the clutch to stop the machine, an electric circuit for the solenoid, a normally open switch in the circuit, a switch control lever engaged by each can in passing to the machine to momentarily close the switch, a normally closed switch in the circuit, a post engaged by each cover in passing to the machine to momentarily open the switch; said covers being timed in their delivery to the machine so that the latter switch is open during closed periods of the first switch; said circuit being closed by the closing of the first switch incident to the closed condition of the second switch by reason of the absence of a can cover being delivered in regular order. 25. In a can closing machine, the combination with means for feeding can parts in regular order to the machine and a drive mechanism including a releasable clutch for disconnecting the drive, of a clutch releasing means comprising a clutch shifting member, an element moved continuously by connection with the drive mechanism, a movable abutment member and means operable automatically incident to irregularity in delivery of can parts to the machine to move the abutment member to a position at which it provides an operative connection between the clutch shifting member and continuously moving element whereby the latter causes release of the clutch. 26. In a can closing machine, the combination with means for feeding can parts in regular order into the machine, and a drive mechanism including a releasable clutch for disconnecting the drive, of clutch releasing means comprising a clutch shifting lever, a member continuously oscillated by connection with the drive mechanism, movable abutment member carried by the clutch shifting lever and means operable automatically incident to irregularity in the delivery of can parts to the machine to cause said abutment member to be adjusted into the path of the oscillating member to cause the latter to effect movement of the clutch shifting lever to release the clutch, and manual means for resetting the clutch. 27. A can closing machine comprising a series of continuously traveling seaming units, a clincher mechanism including a series of continuously traveling clincher units, devices for receiving filled cans brought thereto promiscuously for spacing, timing and delivering them in regular order to the clincher units, means for feeding can covers in regular order to the clincher units for assembly with the cans, devices for transferring the cans from the clincher units without stop to the seamer units, a driving means for the machine including a releasable clutch and means operable incident to discontinuation of the delivery of covers to release the clutch. 28. A can closing machine comprising a series of continuously traveling seaming units, a clincher mechanism including a series of continuously traveling clincher units, devices for receiving filled cans brought thereto promiscuously for spacing, timing and delivering them in regular order to the clincher units, means for feeding can covers in regular order to the clincher units for assembly with the cans, devices for transferring the cans from the clincher units without stop to the seamer units, a driving means from the machine including a releasable clutch, means adapted to be electrically energized to effect release of the clutch, an electric circuit for said means, a normally open switch in the circuit adapted to be momentarily closed by the passing of each can to the machine, a normally closed switch in the circuit adapted to be momentarily opened incident to passing of each cover into the machine; said covers being timed in their delivery to open the latter switch during closed intervals of the first switch and said circuit being completed by the closing of the first switch incident to a closed condition of the second switch by reason of non-delivery of covers in regular order. 29. A can closing machine comprising a series of continuously traveling seaming units, a clincher mechanism including a stationary can rail and a series of continuously traveling units for presenting cans successively to the rail, means for receiving filled cans delivered thereto in promiscuous order for spacing, timing and delivering cans at a gradually accelerated speed to the clincher units, means for feeding can covers to the clincher units for assembly thereby with the cans, devices for transferring the cans at an accelerated speed from the clincher units to the units of the seamer, and, means associated with the can feed mechanism and with the cover feed mechanism whereby any omission in the delivery of cans in regular order to the machine will cause a like omission in the delivery of covers to the machine. 30. A can closing machine comprising a series

- of continuously traveling seaming units, a clincher mechanism including a stationary can rail and a series of continuously traveling units for presenting cans successively to the rail, means for receiving filled cans delivered thereto in promiscuous order for spacing, timing and delivering cans at a gradually accelerated speed to the clincher units, means for feeding can covers to the clincher units for assembly thereby with the cans, devices for transferring the cans at an accelerated speed from the clincher units to the units of the seamer, and means associated with the can feed mechanism and with the cover feed mechanism whereby any omission in the delivery 5 of cans in regular order to the machine will cause a like omission in the delivery of covers to the machine, a driving means for the machine including a releasable clutch, and means operable automatically incident to discontinuation of the feeding of covers to release the clutch. 10
31. In a can closing machine, a seaming head adapted to be coaxially applied to a can for seaming an end thereto, a pair of slides in the head, seaming rolls for first and second seaming operations mounted at the opposite ends of each slide, a member in the head adjustable from neutral position toward and from the plane of the slides and means operatively connecting it with the slides whereby its adjustment in one direction brings the first operation rolls into seaming position and its adjustment in the other direction brings the second operation rolls into seaming position. 15
32. In a can closing machine, a seaming head adapted to be applied to a can coaxially thereof, a pair of slides mounted in the head each with seaming rolls at its opposite ends for first and second seaming operations respectively, a member movable within the head in opposite directions from a neutral position, means connecting 20 said member with the slides whereby its movement in one direction causes the slides to move to bring the first operation rolls into seam forming position, and whereby movement in the opposite direction removes the first rolls from the seam and brings the second operation rolls into seam forming position. 25
33. In a can closing machine, a seaming head adapted to be applied to a can and to be revolved in co-axial relation thereto, a pair of parallel slides mounted in the head for movement in a plane at a right angle to its axis, rolls at opposite ends of the slides for performing different seaming operations, a sleeve axially adjustable in the head in opposite directions from a neutral 30 position, links connecting the sleeve with the slides
- whereby movement of the sleeve in one direction causes the slides to be moved to bring corresponding rolls into seam forming position and its adjustment in the opposite direction from neutral position to adjust the slides to bring the other set 35 of rolls into seam forming position. 30
34. In a can closing machine, a seaming head adapted to be co-axially applied to a can for seaming a cover thereto, a chuck for fitting within the cover at the inside of the seam, a pair of parallel slides mounted in the head for adjustment in a plane at a right angle to its axis, rolls for first seaming operation carried at opposite ends of the slides, rolls for second seaming operation carried at the other ends of the two slides, a sleeve axially adjustable in the head in opposite directions from a neutral position, links connecting the sleeve with the slides whereby its movement in one direction causes the slides to be moved to bring the first operation rolls into seaming position at diametrically opposite sides of the chuck, and its adjustment in the opposite direction adjusts the slides to move the second operation rolls into seaming position at diametrically opposite sides of the chuck. 40
35. In a machine of the character described, the combination with means for conveying can covers with an intermittent movement, of means for applying marks of identification to said covers comprising a rotatably mounted lower carrier, 45 with a series of dies mounted therein for adjustment by the carrier into position for engaging a cover, a reciprocally actuated bar, an upper carrier rotatably mounted by the bar with a series of dies therein complementary to those of the lower 50 carrier and operable against the cover in opposed relation to the die of the lower carrier to impress a mark therein, and a yieldable latch associated with each carrier whereby it may be held in any of its various positions of adjustment. 100
36. In a machine of the character described, the combination with means for conveying can covers with an intermittent movement, of means for applying marks of identification to said covers, comprising a support having a fixed stud, a 55 slide reciprocable toward and from the support and having a fixed stud, die carriers rotatably mounted on the studs, a series of dies in the carriers operable against opposite sides of the covers in opposed relation to impress identifying marks 115 therein, a latch yieldably mounted in each stud and adapted to engage with the carrier thereon to hold it at any position of adjustment. 115
